UNITED STATES PATENT OFFICE.

ANSEL R. KAY, OF DAVENPORT, IOWA.

BOUNCING TOY.

Application filed June 30, 1923, Serial No. 648,712.

To all whom it may concern:

Be it known that I, ANSEL R. KAY, a citizen of the United States, residing at Davenport, in the county of Scott and State 5 of Iowa, have invented certain new and useful Improvements in Bouncing Toys; and I do hereby declare the following to be a full, clear, and exact description of the invention, such as will enable others skilled in 10 the art to which it appertains to make and use the same.

This invention relates to a toy designed for bouncing, rolling and somersaulting which will amuse and fascinate and may 15 be constructed so as not to injure a child if struck with the toy by another child in the heat of play.

Particularly an aim is to provide a toy adapted to be dropped or thrown having a 20 resilient member to bounce from one end of a passageway to the opposite end to cause the toy to somersault in landing and to assume different positions in landing proportional to the rebound of said member.

Another important object is to provide 25 such a toy designed to represent a character and utilizing a tube for travel of a resilient ball therein and which tube has its ends closed by cloth or other means to be engaged by the ball.

Additional objects and advantages will 30 become apparent from a consideration of the specification herein after following taken in connection with the accompanying 35 drawing illustrating one practical embodiment.

In said drawing:—

Figure 1 is a front elevation of the toy;

Figure 2 is a central section on line 2—2

40 of Figure 1, and

Figure 3 is a view similar to Figure 2 but showing the toy inverted.

In the several views, like reference characters designate like or similar parts.

45 In reducing the toy to practice, I provide a tube 4 which is preferably open at both ends and may be made from paste board in order to retain its shape and yet not be harmful to a child if struck therewith. If preferred, the tube may be made of metal or any other material. Surrounding the tube 4, is a cloth covering 5. Tube 4 is closed at the lower end by a flexible pocket 6, which may be made of cloth, and 50 stitched at 7 to the tube 4. At the opposite end of the tube 4, is a cloth or other flexible

pocket 8, stitched to the same as at 9 and over which stitching 9 a band 10 is secured, as by stitching, to give a better finish and appearance. Within the tube 4 and pockets 60 6 and 8, a rubber or other resilient ball 11 is adapted to travel, and which is preferably of less diameter than that of the tube or pocket.

The toy may be representative of any suitable figure or object and to this end the cloth tube 5 may have a face of a clown delineated thereon as at 12 and the pocket 8 suitably decorated to form a head covering. A flexible or cloth body 13 may be 70 secured to the tube 5 as at 14, enclosing the pocket 6. This body is representative of that of clown and particularly includes arms 15 and legs 18.

In use, the toy is adapted to be dropped 75 directly upon the ground or forcibly thrown onto the ground or against a wall, so that the ball 4 will strike the same and on the rebound will travel from one pocket to the other pocket causing the toy to somersault 80 and move accordingly, landing either with the pocket 6 or the pocket 8 uppermost, according to and proportional to the degree of rebound of the ball 4.

The fascinating feature of the doll is that 85 at times it will, after having been bounced, land and remain standing on its head while at other times it will land and remain in a sitting position. With practice, the doll may be thrown to the floor so as to rebound 90 upon a chair or box, alighting and retaining, at times, the first mentioned positions. It may also be made to rebound through a hoop, or to hurdle an object, so placed for that purpose.

95 It is to be understood that I have shown merely one form or construction whereby my objects are attained and the invention is practiced, in view of which facts, various changes in the details of construction and 100 employment of means to accomplish the function may be resorted to within the spirit and scope.

What I claim as my invention is:—

1. A toy having a resilient member to impart movement to the toy through impact, and said toy having a space in which said member travels to determine the landing position of the toy, the resiliency of said member being sufficient to be unaffected by 110 the covering of the toy and to carry the toy into the air after impact.

2. A toy having a resilient member to impart movement thereto, said toy having a space in which said member travels to determine the landing position of the toy, 5 means at opposite ends of the space to receive said member and to permit impact engagement thereof with an obstacle, the resiliency of said member being sufficient to be unaffected by the covering of the toy and 10 to carry the toy into the air after impact.
3. A toy having a resilient member to impart movement thereto and means at each end of the toy to receive said member to permit impact thereof with an obstacle, the 15 resiliency of said member being sufficient to be unaffected by the covering of the toy and to carry the toy into the air after impact.
4. A toy having a tube, pockets at the 20 ends of said tube, and a resilient member to impart movement to the toy through impact with an object, said member being movable in said tube and pockets, and of sufficient resiliency to be unaffected by the 25 covering of the toy and to carry the toy into the air after impact.
5. A toy having a resilient member to impart movement thereto through impact, having a tube in which said member travels, 30 and flexible pockets at opposite ends of the tube into which said member extends, the resiliency of said member being sufficient to be unaffected by the covering of the toy and to carry the toy into the air after impact.
- 35 6. A toy having a resilient member to impart movement thereto through impact, consisting of a tube, a covering for said tube, flexible pockets at opposite ends of the tube secured to said covering, and said resilient member consisting of a ball to travel 40 in said tube and pockets, the resiliency of said member being sufficient to be unaffected by the covering of the toy and to carry the toy into the air after impact. 45
7. A toy having a resilient member to impart movement thereto through impact, consisting of a tube, a covering on said tube having a face delineated thereon, pockets stitched to said covering to close opposite ends of the tube, said pockets being of flexible material stitched to the covering, said member being disposed to travel in said tube and pockets, and a body stitched to said covering, the resiliency of said member being sufficient to be unaffected by the 55 covering of the toy and to carry the toy into the air after impact.
8. A toy comprising a tube, pockets of flexible material secured to the ends of said tube, and a rubber ball loosely retained in 60 said tube, said ball rebounding on impact with an object and carrying the retaining tube and pockets into the air after impact.

In testimony whereof I affix my signature in presence of two witnesses.

ANSEL R. KAY.
